UNITED STATES PATENT OFFICE.

JOSEPH LIEBERMAN, OF PHILADELPHIA, PENNSYLVANIA.

SERVICE TROUSERS.

Application filed January 6, 1923. Serial No. 610,959.

To all whom it may concern:

Be it known that I, JOSEPH LIEBERMAN, a citizen of the United States, residing at Philadelphia, county of Philadelphia, State of Pennsylvania, have invented new and useful Service Trousers, of which the following is a specification.

In service trousers such as knickerbockers, riding breeches and the like for men, 10 women and children, it has heretofore been deemed necessary to provide the overlapping calf engaging portion of the trousers with straps or buttons and button-holes, in order to obtain the proper fit at the calf 15 of the leg and it is usually customary to have the set of the trousers at the calf engaging portion adjustable which can ordinarily be provided for by the lacing or the positioning of the button.

20 The object of my present invention is to devise a novel construction of knickerbockers wherein the front calf engaging portion will be a continuation of the leg portion of the trousers and the rear calf engaging portion will be formed of elastic material such as, for example, a knitted fabric, or one which will have the desired amount of stretch or elasticity, so that a snug fit will be formed at the calf of the leg.

25 Another object is to reduce the amount of material employed, the elastic material being cheaper than the cloth, and of such dimensions that the seam which forms the means for uniting the elastic material with the cloth of which the trousers are made 30 will form a continuation of the side seams of the trousers or knickerbockers.

With the above and other objects in view which will hereinafter more fully appear, 40 my invention comprehends a novel construction of knickerbockers wherein substantially one-half of the calf engaging portion is of elastic material, such as a knitted or woven fabric, so that when the knickerbockers are 45 drawn into proper position, the proper fit and set will be provided at the calf engaging portions of the knickerbockers and the necessity of lacing, buckling or buttoning the parts together at such point is entirely 50 obviated.

It further comprehends other novel features of construction and advantage all as will be hereinafter fully set forth and described.

55 For the purpose of illustrating my inven-

tion, I have shown in the accompanying drawing a typical embodiment thereof which is at present preferred by me, since this embodiment will be found in practice to give satisfactory and reliable results. It 60 is, however, to be understood that the various instrumentalities of which my invention consists can be variously arranged and organized and that my invention is not limited to the precise arrangement and organization of these instrumentalities as herein shown and described.

Figure 1 represents a rear elevation of a pair of knickerbockers, embodying my invention.

70 Figure 2 represents, in perspective, the calf engaging portion of one leg of the trousers.

Similar numerals of reference indicate 75 corresponding parts.

Referring to the drawings, 1 designates a pair of knickerbockers, embodying my invention. These knickerbockers are adapted for use by men, women and boys and may be constructed of any desired material and 80 in any desired manner according to the use to which they are to be put, the only change in construction being at the calf engaging portion of the legs.

At this point, the front face of the leg 85 of the trousers is extended in the usual manner, as at 2, while the rear portion of the calf engaging portion is formed from elastic material 3, which in practice is preferably knitted or woven cloth, the shape of the 90 blank being clearly shown in Figure 1. It will be seen that the elastic portion 3 consists of a strip of material substantially one-half of the calf engaging portion for the sake of economy of manufacture.

95 This elastic strip 3 at its upper end has the diverging top edge 4 which diverges downwardly and outwardly. The sides edges are secured to the portion 2 by means of a line of stitching 5 forming the side 100 seams. The upper edge at 4 is stitched to the rear portion 6 of the cloth of which the trouser legs are made.

105 It will be apparent that in accordance with my present invention, when the knickerbockers are drawn on to the wearer, the calf engaging portions will assume their proper position around the calf of the wearer so that a neat and snug fit is provided and the fullness of the knickerbockers at the knee 110

can be folded over in the usual manner so that the proper set and fit of the garment will be obtained.

I am also enabled to provide an economy in manufacture since the elastic material is cheaper than the cloth of which the knickerbockers are made and the cost in labor is less than is usually present in the manufacture of knickerbockers, since the cost of the buttons and of making the buttonholes is eliminated or the cost of the eyelets, in case a lacing is employed.

The garment is quickly adjusted by simply drawing it into position and can also be removed in a minimum amount of time. The front of the knickerbockers will have the same appearance at the calf engaging portion as at the leg and hip engaging portion of the trousers, as it is made of the same material and the elastic portion at the rear is substantially covered by the stockings which are rolled over it and by the fold of the leg portion of the knickerbockers.

It will now be apparent that I have devised a new and useful service trousers which embodies the features of advantage enumerated as desirable in the statement of the invention and the above description, and while

I have, in the present instance, shown and described a preferred embodiment thereof which will give in practice satisfactory and reliable results; it is to be understood that this embodiment is susceptible of modification in various particulars without departing from the spirit or scope of the invention or sacrificing any of its advantages.

Having thus described my invention, what I claim as new and desire to secure by Letters Patent, is:

Service trousers having the front leg portions formed of fabric extended to form the front half of the calf engaging portions, the rear leg portions of the trousers being formed of fabric terminating in the rear of the front calf engaging portions of the leg fabric, the rear calf engaging portions being of knitted fabric connected at their upper marginal portions to the rear leg portions and being connected with the side marginal portions of the front calf engaging portions by the same lines of stitching as those which unite the front and rear leg portions.

JOSEPH LIEBERMAN.
